UNITED STATES PATENT OFFICE.

ISAAC ST. CLAIR GOLDMAN, OF LOS ANGELES, CALIFORNIA, ASSIGNOR OF
ONE-HALF TO SAMUEL L. KISTLER, OF LOS ANGELES, CALIFORNIA.

TRITURATOR.

SPECIFICATION forming part of Letters Patent No. 774,067, dated November 1, 1904.

Application filed December 23, 1903. Serial No. 186,319. (No model.)

To all whom it may concern:

Be it known that I, ISAAC ST. CLAIR GOLDMAN, a citizen of the United States, and a resident of Los Angeles, in the county of Los Angeles and State of California, have invented a new and Improved Triturator, of which the following is a full, clear, and exact description.

The object of the invention is to provide a new and improved triturator arranged to insure a proper reduction of the substance to be treated by causing the pestle to be moved across the bottom of the mortar very rapidly on giving the pestle a pounding motion or allowing the pestle to work on the sides of the mortar or to pass slowly across the entire bottom or up the sides of the mortar, according to the nature of the substance under treatment, to insure perfect grinding without danger of clogging or cramping or fouling the machine, especially when treating gummy substances.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the triturator, the mortar being shown in section. Fig. 2 is a plan view of the same. Fig. 3 is an elevation of one end of the machine. Fig. 4 is a like view of the other end of the machine, and Fig. 5 is a face view of a set of interchangeable cams for use in the machine according to the nature of the substance to be triturated.

The mortar A, in which operates a pestle B, is set with its base on a disk C and held centrally thereon by set-screws C', and from the bottom of the disk C depends a shaft D, journaled in suitable bearings carried by a bracket E and the base E' of the machine, as plainly illustrated in Figs. 1 and 3. On the shaft D is secured a bevel gear-wheel D', in mesh with a bevel gear-wheel F', fastened on the main shaft F of the machine and journaled

in suitable bearings on the bracket E, the said main shaft F carrying a pulley F², connected by belt with other machinery for imparting a rotary motion to the shaft F. The rotation of the latter is transmitted by the gear-wheels F' and D' to the shaft D, and consequently to the disk C and the mortar, A to provide a revolute mortar, in which operates the revolute pestle B, as hereinafter more fully described.

The pestle B is journaled with the upper end of its shank B' in a bearing G, provided with trunnions G', journaled in one end of a walking-beam H, hung on a shaft H', carried by a standard E², erected on the base-plate E'. A spring G² is coiled on one of the trunnions G' and secured at one end of the walking-beam and presses with its other end on the shank of the pestle B to hold the same in contact with the side of the mortar A, as will be readily understood by reference to Figs. 1 and 3.

The outer end of the walking-beam H is connected by a link I with the free end of a lever J, fulcrumed at J' on the standard E², and on the said lever J is journaled a flanged friction-roller J², engaged by the peripheral face of one of a set of cams K of different shapes and adapted to be interchangeably secured on a shaft L, journaled in suitable bearings on a bracket E³, attached to the base-plate E'.

On the shaft L is secured a sprocket-wheel L', connected by a sprocket-chain L² with a sprocket-wheel L³, secured on a shaft N, extending transversely and journaled in the lower portion of the standard E². On the shaft N is secured a sprocket-wheel N', connected by a sprocket-chain N² with a sprocket-wheel N³, fastened on the main shaft F, so that when the latter is rotated a rotary motion is given to the shaft N, and by the connection described the shaft N causes rotation of the cam-shaft L for the cam K to impart a swinging motion in a downward direction to the lever J to cause the link I to rock the walking-beam H and move the pestle B up or down in the mortar A.

The pestle B is revolute and is driven from

the shaft N, and for the purpose described the shank B' of the pestle is provided with a bevel gear-wheel O, in mesh with a bevel gear-wheel O', mounted to turn loosely on one of the 5 trunnions G', and on the bevel gear-wheel O' is secured a sprocket-wheel O², connected by a sprocket-chain O³ with a sprocket-wheel O⁴, mounted to rotate loosely on the shaft H', which forms the fulcrum for the walking-beam H. On the shaft of the sprocket-wheel O² is secured a sprocket-wheel O⁵, connected by a sprocket-chain O⁶ with a sprocket-wheel O⁷, secured on the shaft N, so that when the latter is driven from the main shaft F, as 10 previously explained, then a rotary motion is given by the sprocket-wheel O⁷, sprocket-chain O⁶, sprocket-wheels O⁵ and O⁴, sprocket-chain O³, sprocket-wheel O², and gear-wheels O' and O to the pestle B, so as to rotate the 15 latter in an opposite direction to the rotation of the mortar A and at the time the pestle B moves up and down by the action of the walking-beam H.

It will be seen that by having an irregularly-shaped cam K an irregular rocking motion is given to the walking-beam H, and consequently an irregular rocking movement to the pestle B to allow of moving the latter rapidly up or down or slowly up and down or 20 very rapidly up or down, according to the nature of the substance to be triturated.

It is understood that when the main shaft F is rotated as described then a rotary motion is given to the mortar A, and at the same 25 time the pestle B is rotated and moved up and down by the action of the walking-beam H, having an irregular movement caused by the shape of the corresponding cam K, held detachably on the shaft L, as before explained.

40 The machine described is very simple and durable in construction, and a very effective reduction or trituration of the substance is had by the action of the revolving mortar A and the revolving and up-and-down moving pestle 45 B, pressed on by the spring G².

Having thus described my invention, I claim as new and desire to secure by Letters Patent—

1. A triturator having a revoluble mortar, a pestle, means for rotating the pestle, and means 50 for moving the pestle up and down and a spring pressing the pestle laterally against the mortar, as set forth.

2. A triturator having a revoluble mortar, a pestle, means for rotating the pestle, and means 55 for moving the pestle up and down and controlled by a cam and a spring pressing the pestle laterally against the mortar, as set forth.

3. A triturator provided with a mortar, a 60 pestle for the same, a support for the pestle, a bearing provided with trunnions journaled in the support, said bearing carrying a pestle, means for turning the pestle and a spring coiled on one of the trunnions and bearing be- 65 tween the same and the shank of the pestle

whereby to press the pestle laterally against the side of the mortar as set forth.

4. The combination of the mortar, the pestle movable both longitudinally and laterally in the mortar whereby it may rise and fall there- 70 in and may press laterally against the side of the mortar as it rises and falls, and a spring acting upon the pestle and pressing the same laterally against the side of the mortar, substantially as set forth. 75

5. A triturator provided with a revoluble pestle having an irregular up-and-down movement and a spring pressing the pestle laterally against the mortar whereby it may follow irregularities in the mortar and contents, as 80 set forth.

6. A triturator having a mortar, a pestle for the same, a cam-controlled mechanism for imparting an irregular up-and-down movement to the pestle and a spring acting upon the upper end of the pestle to press the lower end of same laterally against the mortar, as set forth. 85

7. A triturator comprising a mortar, a pestle for the same, a walking-beam to which the pestle is pivoted at its upper end, and a cam mechanism for imparting a rocking motion to the walking-beam, as set forth. 90

8. A triturator comprising a revoluble mor- 95 tar, a pestle for the same, a walking-beam to which the pestle is pivoted at its upper end, and a cam mechanism connected with the walking-beam, to impart an irregular rocking motion to the same, as set forth.

9. A triturator comprising a revoluble mor- 100 tar, a pestle for the same, a walking-beam to which the pestle is pivoted, a cam mechanism connected with the walking-beam, to impart an irregular rocking motion to the same, a spring for actuating the pestle laterally and 105 means for imparting a rotary motion to the said pestle, as set forth.

10. A triturator comprising a main shaft, a mortar rotated from the said shaft, a pestle for the mortar, rotated from the said shaft, a walking-beam in which the pestle is journaled, and a cam mechanism connected with the walking-beam and driven from the said shaft, as set forth. 110

11. A triturator comprising a mortar, a walk- 115 ing-beam extending at one end over the mortar, a pestle swung pivotally from the walking-beam above the mortar whereby the pestle may move up and down with the walking-beam and may swing laterally on its connec- 120 tion with the beam to press against the sides of the mortar, and a spring operating between the beam and the pestle to press the latter laterally against the mortar.

12. The combination of the mortar, the pes- 125 tle, the walking-beam, a bearing supporting the pestle and having trunnions journaled to the walking-beam, operating-gearing carried by the bearing for rotating the pestle, and a spring supported by the bearing and having 130

a portion acting upon the shank of the pestle to press the same laterally against the side of the mortar, substantially as set forth.

13. A triturator having a mortar, a revolvable pestle, a walking-beam, in one end of which the said pestle is journaled, a lever, a link connecting the lever with the other end of the walking-beam, and an irregularly-shaped cam engaging the said lever, as set forth.

14. A triturator having a mortar, a pestle for the mortar, a walking-beam, in one end of which the said pestle is journaled, a lever carrying a friction-roller, a link connecting the lever with the other end of the walking-beam, an irregular cam engaging the said friction-roller, and a main shaft connected with the said mortar, the said pestle and the said cam, as set forth.

15. A triturator provided with a mortar, a pestle for the same, a walking-beam, a bearing hung on the walking-beam and in which

the pestle is mounted to turn, means for rotating the pestle, and a spring for pressing the pestle laterally in contact with the side of the mortar, as set forth.

25

16. The combination of a mortar, a walking-beam, a standard to which said walking-beam is pivoted, a pestle pivoted to the swinging end of the walking-beam over the mortar, gearing on the pestle and walking-beam and 30 meshed together, a sprocket-chain for driving said gearing, a sprocket-wheel concentric with the pivot of the walking-beam for driving said sprocket-chain and means for driving said sprocket-wheel.
